P. C. HALDEMAN.
STRIPPER FOR ROLLING MILLS.
APPLICATION FILED SEPT. 4, 1919.

Patented Dec. 27, 1921.

2 SHEETS—SHEET 2.

Fig. 4.

UNITED STATES PATENT OFFICE.

PAUL C. HALDEMAN, OF COATESVILLE, PENNSYLVANIA, ASSIGNOR TO LUKENS STEEL COMPANY, OF COATESVILLE, PENNSYLVANIA, A CORPORATION OF PENNSYLVANIA.

STRIPPER FOR ROLLING-MILLS.

1,401,773.

Specification of Letters Patent. Patented Dec. 27, 1921.

Application filed September 4, 1919. Serial No. 321,514.

To all whom it may concern:

Be it known that I, PAUL C. HALDEMAN, a citizen of the United States, residing in Coatesville, Chester county, Pennsylvania, 5 have invented certain Improvements in Strippers for Rolling-Mills, of which the following is a specification.

My invention relates to rolling mills, and it consists of certain improvements in the 10 means employed therewith for guiding the front ends of plates emerging from between the rolls. One of the principal objects of my invention is to provide a simple and efficient stripper that will insure the guidance 15 of the rolled plates onto the roller table, and will act to clean the lower roll of any scale, cinder or the like which may be dropped by the plates. Additionally my improved stripper is so designed as to readily dis- 20 charge therefrom any such foreign material so received.

My invention includes a rest bar extending across the mill at a point in advance of the lower roll and at a suitable distance there- 25 from, with a removable stripper adapted to be carried by said rest bar; the latter having seats specially arranged to receive the stripper and being further equipped with suitable securing means therefor. 30 Preferably I employ a plurality of removable stripper sections, as clearly shown in the drawings and referred to in the specification.

These and other features of my invention are more fully described hereinafter, reference being had to the accompanying drawings, in which:

Figure 1, is a plan view of a rest bar and stripper carried thereby, within the 40 scope of my invention.

Fig. 2, is a front elevation of the same.

Fig. 3, is a sectional view on the line III—III, Fig. 2, illustrating the rest bar and a stripper carried thereby.

Fig. 4, is a view similar to Fig. 3, illustrating a modification within the scope of my invention, and

Figs. 5 and 6, are views illustrating other modified arrangements of the stripper with- 50 in the scope of my invention.

In its broadest aspect, my invention comprises a structure of the type shown in Fig. 5, in which I have shown a stripper 1, de- 55 signed to extend across the mill in advance of the lower roll (shown by dotted lines at

2) and having a stripping edge 1^a, lying in engagement with the lower roll.

I have illustrated in Fig. 6, a similar structure, having in addition a plate 3 resting against the roll 2 beyond the stripping edge 1^a, for the purpose of cleaning cinder, scale, and any other foreign matter from the same. This plate may be carried by a bolt (or bolts) 4, pivoted to the stripper at 5, so as to gravitate into contact with the roll.

The upper portion of the stripper shown in Figs. 5 and 6, is notched, as indicated at 6, throughout its length to provide recesses into which scale, cinder and other 70 foreign matter carried by the plate or produced under the rolling operation may fall and be carried away by gravity so as to avoid being rolled into the plate. Projections or lugs 7, preferably narrow, are 75 provided between said recesses 6, over which the plates may pass to the roller table.

The preferred form of my improved construction is illustrated in Figs. 1, 2, 3 and 4. In Figs. 1 and 2, a rest bar is shown at 10, 80 and while it is shown in these views as partly broken away, it will be understood that it extends across the full width of the mill, and is provided with ends 11 for support in suitable stirrups or other means at 85 the side housings of the mill. This rest bar has a beveled upper edge 12, and is provided at intervals with stepped projecting portions or ribs 13, rising from said beveled edge, and notched at 14 lengthwise of the 90 bar.

Adapted to be supported by the rest bar is a stripper 1^c consisting of a plurality of elements 15, having relatively thin edges 1^b adapted to engage the surface of the roll, 95 (indicated by dotted lines at 2^a); thereby serving to guide the plate away from the same and onto the roller table, and extending rearwardly from this thin edge of the rest bar are a series of ribs 7^a shaped on 100 their under side to engage the stepped and notched portion of the rest bar. Additionally, the rear surface of the thin edge 1^b is beveled at 6^a so that cinder, scale and the like, dropping from the plate, will be freely 105 discharged therefrom and pass onto and over the beveled surface 12 of the rest bar.

The stripper sections may be prevented from rising from the rest bars by means of eye-bolts 20, pivotally connected at 21, to 110

lugs 22, carried by said stripper sections and adapted to pass through apertures 23, in shoulders 24, carried by the rest bar; the latter being recessed at 25 to accommodate 5 the eye-bolts and keep them clear of the roll. Preferably a cotter pin 26 will be provided to retain the eye-bolt in place.

The construction shown in Fig. 4, is substantially like that shown in Fig. 3, except 10 that a spring 27 may be carried by the eye-bolt to hold the stripper sections against the rest bar; bearing plates 28 being provided for the ends of the spring, and a nut 29 being threaded onto the end of the eye- 15 bolt.

I claim:

1. The combination, with a roll of a rolling mill, of a stripper having a thin edge arranged to contact with the roll and having 20 its upper surface provided with ribs, with recesses between said ribs for the discharge of cinder, scale and the like.

2. The combination, with a roll of a rolling mill, of a stripper having a thin edge arranged to contact with the roll and having 25 its upper surface provided with ribs, with recesses between said ribs; said recessed portions having inclined surfaces for the discharge of cinder, scale and the like.

3. The combination, with a roll of a rolling mill, of a rest bar, and a stripper mounted thereon and having a thin edge arranged to contact with the roll and having its upper 35 surface provided with ribs, with recesses between said ribs for the discharge of cinder, scale and the like.

4. The combination, with a roll of a rolling mill, of a rest bar, and a stripper mounted thereon having a thin edge arranged to 40 contact with the roll and having its upper surface provided with ribs, with recesses between said ribs; said recessed portions having inclined surfaces for the discharge of cinder, scale and the like.

5. The combination, with a roll of a rolling mill, of a rest bar mounted adjacent to the roll, a stripper mounted upon said rest

bar and adapted to engage the roll; said stripper having its upper surface recessed, with ribs between the recesses for supporting 50 engagement with a plate passing over the roll, and means for securing said stripper plate to the rest bar.

6. The combination, with a roll of a rolling mill, of a rest bar mounted adjacent to 55 the roll, a stripper made of a plurality of sections and mounted upon said rest bar and adapted to engage the roll; said stripper sections having their upper surface recessed, with ribs between the recesses for engagement with a plate passing over the rolls; said recessed portions having inclined surfaces, and means for holding said stripper sections to the rest bar.

7. The combination, with a roll of a rolling mill, of a rest bar mounted adjacent the roll, and having a beveled upper surface with notched projections extending above the same, a stripper mounted upon said rest bar and engaging said projections and having an edge adapted to engage the roll; said stripper having its upper surface recessed, with ribs between the recesses for engagement with a plate passing over the roll, and means for holding said stripper plate to the 75 rest bar with its thin edge in engagement with the roll.

8. The combination, with a roll of a rolling mill, of a rest bar mounted adjacent the roll, and having a beveled upper surface 80 with notched projections extending above the same, a stripper having a plurality of sections mounted upon said rest bar and engaging said projections and having an edge adapted to engage the roll; said stripper sections having their upper surfaces recessed, with ribs between the recesses for engagement with the plate passing over the roll; said recessed portions having inclined surfaces, and means for holding said stripper 85 plates to the rest bar with their thin edges in engagement with the roll.

PAUL C. HALDEMAN.
